UNITED STATES PATENT OFFICE.

JOSEPH GUAY, OF MISSOULA, MONTANA, ASSIGNOR TO JOSEPH S. KESSLER AND ARCHIEBALD ARTHUR LANGLOIS, BOTH OF MISSOULA, MONTANA.

BILLIARD-CUE CHALKER.

Application filed December 13, 1922. Serial No. 606,731.

To all whom it may concern:

Be it known that I, JOSEPH GUAY, a citizen of the United States, residing at Missoula, in the county of Missoula and State 5 of Montana, have invented certain new and useful Improvements in a Billiard-Cue Chalker, of which the following is a specification.

The present invention relates to a billiard 10 cue chalker and has for its principal object to provide convenient means for supporting cue chalk so that it may be applied to the tip of a billiard cue efficiently and with considerable ease.

15 Another important object of the invention is to provide a device of this nature which may be conveniently located and which will be automatic in operation as well as adjustable so as to be operable under 20 varying circumstances.

A still further important object of the invention is to provide a device of this nature which will be simple and efficient in construction, reliable in operation, attractive in appearance, accessible, durable, comparatively inexpensive to manufacture, and generally well adapted to the purpose for 25 which it is designed.

With the above and numerous other objects in view as will appear as the description progresses, the invention resides in certain novel features of construction, and the combination and arrangement of parts as will be hereinafter more fully described 35 and claimed.

In the drawings—

Figure 1 is an elevation of the device embodying my invention.

Figure 2 is a longitudinal section there- 40 through, and

Figure 3 is a detail section taken sub- 45 substantially on the line 3—3 of Figure 1 looking in the direction of the arrow.

Referring to the drawing in detail it 50 will be seen that the bracket which is constructed especially for this device consists of a plate 1 which may be fastened to a support in any suitable manner such as by screws 2. A casing or housing is formed 55 on this plate 1 and includes the fixed portion 3 comprising a pair of right angularly disposed walls having a flange 4 fixed to the plate 1 and the movable portion 5 also consists of two right angularly disposed 60 walls one of which is hingedly connected to

one of the walls of the other portion 3 as at 6 whereby the housing may be opened for access to the interior thereof for a purpose as will appear later. A spring 65 clip 7 holds the movable portion 5 in closed relation to the fixed portion 3. An apertured ear 8 is disposed on the plate 1 inferiorly of the housing and has disposed on one face an annular series of ratchet teeth.

The chalker proper consists of an inner 70 member 9 and an outer member 10 telescopedly associated therewith. The inner member 9 is in the form of a cylindrical block having a spiral groove 11 arranged on its curved periphery. This inner member 9 is fixed to a shank or stem or bracket arm 12 which terminates at one end in a disk 13 having on its face a plurality of annularly arranged ratchet teeth for association with the ratchet teeth on the ear 75 8. A bolt 14 extends from the disk 13 through the apertured ear 8 so that the ratchet teeth may be locked in engagement with each other by a thumb nut 15 or in any other suitable manner. Thus it will 80 be seen that the chalker may be disposed in various angular relations to the plate 1 it being noted that one wall of the fixed portion 3 of the housing is provided with a slot through which the shank 12 extends. 85

The outer member 10 is in the form of a cylindrical tube having an apertured closure trap 16 screwed or otherwise fixed to one end and a cup shaped member 17 attached to the other end. This cup shaped 90 member 17 supports a cone shaped guide 18. A chalk receptacle 19 is disposed in the adjacent end of the inner member 10 and a block of chalk 20 is disposed therein. It will be noted that a cue stick may be inserted through the cup shaped member 17 and the guide 18 will direct the tip in engagement with the chalk 20 disposed in the receptacle 19. A pair of lugs 21 are disposed on the outer member 10 so as to project inwardly thereof and engage the spiral groove 11 of the inner member 9. These lugs may be of any preferred construction and in the present instance are merely illustrated as rivets the heads thereof being positioned in the spiral groove 11. It will thus be seen that as the outer member is moved in relation to the inner member it will rotate. Therefore, as the billiard cue 95 is inserted so that the tip engages the chalk 100 105 110

20 and pushed further it will cause the rotation of the outer member 10 thereby thoroughly applying the chalk to the billiard tip. In order to return the parts to 5 their position as shown in figure 2 a spring 22 is disposed about the shank 10 having one end fixed thereto and the other end fixed to the outer member 10 and this spring normally retains the parts in the position 10 illustrated in Figure 2.

I have, in the present instance, shown and described the preferred embodiment of my invention which will give in practice satisfactory and reliable results, and it is to 15 be understood that the same is susceptible of modification in various particulars without departing from the spirit or scope of the invention or sacrificing any of its advantages.

20 Having thus described my invention what I claim as new is:—

1. In combination, an adjustable bracket including a stem, a pair of telescopically associated members, one of which is provided 25 with a spiral groove and the other with a lug engageable with the groove, the inner member being attached to said stem, a spring coiled about the stem and having one end engaged with the stem and the other end 30 engaged with the other member, and a chalk holder disposed in one end of the outer member so that when a cue stick is pressed against chalk held in the chalk holder the outer member will be telescoped over the 35 inner member and rotated thereby unwinding the spring and at the same time expanding the same and thus when the cue stick is disengaged from the chalk in the chalk holder said spring will return the outer member to its initial position.

2. In combination, a bracket including a stem, a pair of telescopically associated members, one of which is provided with a spiral groove and the other with a lug engageable with the spiral groove, the inner 45 member being attached to said stem, a spring

coiled about the stem and having one end engaged with the stem and the other end engaged with the outer member, a chalk holder disposed in one end of the outer member, a 50 cup-shaped member disposed on the outer member, and a conical shaped guide in the cup-shaped member leading to the chalk holder, whereby when a cue stick is held against chalk held in the chalk holder the outer member will be telescoped and rotated over the inner member thereby unwinding the coil spring and stretching the same so that when the cue stick is released 55 from the chalk in the chalk holder said outer member will be returned to its initial position.

3. In combination with a chalker for cues, a bracket including a plate, a housing divided into two sections each including a 60 pair of angularly disposed side walls and a triangular shaped end wall, one side wall of one section being provided with a slot, a stem extended through the slot, said chalker attached to the exterior end of said stem, 65 the interior end thereof terminating in a disk having an annular series of ratchet teeth, an apertured ear extending from the plate within the housing and having an annular series of ratchet teeth on one face 70 thereof, a bolt extending from the stem and centrally from the disk thereon through the apertured ear, and a nut on said bolt to hold the ear and disk in engagement with each other so that the teeth prevent rotation of 75 the disk in relation to the ear, one section of said housing being fixed to said plate and the other section being hinged to the fixed section all in the manner and for the purpose specified.

80 In testimony whereof I affix my signature in presence of two witnesses.

JOSEPH GUAY.
